FLASH GUN FOR CAMERAS

Masanao Matsui, Tokyo, Japan, assignor to U.S. Photo Supply Co., Inc., Washington, D.C., a corporation of Delaware

Application October 9, 1959, Serial No. 57,871

Term of patent 14 years

(Cl. D61—1)

FIG. 1.

FIG. 2.

FIG. 3.

FIG. 4.

FIG. 5.

FIG. 6.

Fig. 1 is a right side elevational view of a flash gun for cameras showing my new design.

Fig. 2 is a left side elevational view thereof.

Fig. 3 is a front elevational view thereof.

Fig. 4 is a rear elevational view thereof.

Fig. 5 is a top plan view thereof.

Fig. 6 is a bottom plan view thereof.

The dominant features of my new design are shown in solid lines in the drawing.

I claim:

The ornamental design for a flash gun for cameras, as shown and described.
